US0D1064653S

(12) United States Design Patent (10) Patent No.: US D1,064,653 S
(45) Date of Patent: * Mar. 4, 2025

(54) CABINET

- (71) Applicant: Kohler Co., Kohler, WI (US)
(72) Inventors: Douglas J. Diemel, Jr., Kohler, WI (US); Alexander V. Letourneau, Sheboygan, WI (US); Sandeep Pawar, Maharashtra (IN)
(73) Assignee: Kohler Co., Kohler, WI (US)
() Term: 15 Years
(21) Appl. No.: 29/845,292
(22) Filed: Jul. 6, 2022
(51) LOC (15) Cl. 08-08
(52) U.S. Cl. USPC D6/559
(58) Field of Classification Search
USPC D6/559, 329, 406.3, 553, 561, 634, 659,

(57) CLAIM

The ornamental design for a cabinet, as shown and described.

DESCRIPTION

FIG. 1 is a top, front perspective view of a cabinet according to our new design;

FIG. 2 is a bottom, rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a top, front perspective view with a door open;

FIG. 10 is a bottom, front perspective view with a door open; and,

FIG. 11 is a front view with a door open.

The broken lines of even length illustrating portions of the cabinet form no part of the claimed design. The dot-dash lines define the bounds of the claimed design and form no part of the claimed design. Break lines having a jagged element are not part of the claimed design and show unspecified lengths of the portion are possible. The appearance of any portion of the article between the break lines forms no part of the claimed design.

1 Claim, 9 Drawing Sheets
